United States Patent Office

Des. 177,588
Patented May 1, 1956

177,588

FRONT OF A WALL OVEN

Alfred J. Przybylowicz, Detroit, Mich., assignor to General Motors Corporation, Dayton, Ohio, a corporation of Delaware

Application March 11, 1955, Serial No. 35,002

Term of patent 7 years

(Cl. D81—4)

Fig. 1

Fig. 2

The dominant features of my design reside in the portions shown in full lines.

I claim:

The ornamental design for a front of a wall oven as shown and described.
